(57) **CLAIM**

The ornamental design for a shoe insert, as shown and described.

DESCRIPTION

FIG. 1 is a front perspective view of a shoe insert showing my new design;

FIG. 2 is a rear perspective view of the shoe insert;

FIG. 3 is a front view of the shoe insert;

FIG. 4 is a back view of the shoe insert;

FIG. 5 is a right-side view of the shoe insert;

FIG. 6 is a left-side view of the shoe insert;

FIG. 7 is a top side view of the shoe insert; and,

FIG. 8 is a bottom side view of the shoe insert.

FIG. 9 is a cross-sectional view along Lines A-A and B-B of the shoe insert;

FIG. 10 is a front perspective view mirror image of the shoe insert; and,

FIG. 11 is a bottom perspective view mirror image of the shoe insert.

The broken lines are included for the purpose of illustrating portions of the article that form no part of the claimed design.

1 Claim, 6 Drawing Sheets
